FITTED TRAVELING CASE

Elizabeth N. Graham, New York, N. Y.

Application July 16, 1947, Serial No. 761,286

4 Claims. (Cl. 190—51)

1

The present invention relates to a fitted traveling case of the type in which an auxiliary, separately accessible compartment is provided for articles of cosmetics, toiletries and personal hygiene, such as face powder, perfume, and hair and tooth brushes, and the like.

It is an object of the present invention to provide a traveling case of the character described in which the auxiliary compartment for the articles of cosmetics, toiletries, and the like, which are generally more frequently used than the articles in the main compartment of the traveling case, is readily and conveniently accessible for use, without disturbing the articles in the main compartment of the case.

It is also an object of the present invention to provide a traveling case of the character described in which the auxiliary compartment is of maximum compactness and occupies a minimum amount of space, thereby increasing the capacity of the traveling case as a whole.

It is another object of the present invention to provide a traveling case of the character described which permits the removal of the articles of cosmetics, toiletries, and the like from the auxiliary compartment, either individually or all at once, so that all such articles may be simultaneously removed and taken for use, as into a dressing room, without the necessity of taking the entire case along.

It is still another object of the present invention to provide a fitted traveling case of the character described in which the articles removed from the auxiliary compartment may be safely, securely and conveniently carried en masse and supported on a surface for ready and rapid use and replacement.

The foregoing and other advantages and superiorities of the fitted traveling cases of the present invention will become more readily apparent to those skilled in the art from the embodiment thereof shown in the accompanying drawings and from the description following. It is to be understood, however, that such embodiment is shown by way of illustration only, to make the principles and practice of the invention more readily comprehensible, and without any intent of limiting the invention to the specific details therein shown.

In the drawings:

Fig. 1 is an isometric view of one embodiment of a fitted traveling case of the present invention, shown partly broken away and with both the main and auxiliary compartments open;

2

Fig. 2 is a fragmentary section taken on line 2—2 of Fig. 1;

Fig. 3 is a side elevational view of one embodiment of a mounting board for cosmetics and like articles for the auxiliary compartment, shown removed from the case and resting on a surface in substantially upright position; and

Fig. 4 is a view similar to that of Fig. 3 of another, preferred embodiment of a mounting board for the auxiliary compartment.

Referring more specifically to the accompanying drawings, the traveling case illustrated therein comprises a main body portion or receptacle portion, generally designated as 10, having the bottom 11, side walls 12, rear wall 13, and front wall 14. The rear wall 13 carries a cover 15, hingedly secured thereto in any suitable conventional manner.

The front wall 14 of the body portion 10 is hingedly secured to the bottom 11 thereof in any conventional manner, as by means of the continuous covering and lining materials of the case as shown in the illustrative embodiment of the drawings at 16, permitting the front end of the body 10, as well as the top therefor, to be opened.

The front portion of the body 10 may be partitioned off, as by means of the vertically disposed partition 17, which divides it into the main compartment 18 and the auxiliary compartment 19, the front of which comprises the hinged wall 14, and which is of the same height as the main compartment 18, but of shallow depth.

Arranged within the compartment 19 in upright position, up against the partition 17, is a mounting board 20 for cosmetics and like articles, on the front face of which are arranged straps or similar devices 21, for engaging and supporting bottles, boxes, and like containers and receptacles for cosmetics, toiletries and articles of personal hygiene.

To hold the board 20 in its upright position and in place within the compartment 19, it may be provided, adjacent its upper edge, with a tab 22, which is adapted to overlap the upper edge of the partition 17, and to engage the inner face thereof, as by means of cooperating fastener elements 24, or similar fastening or locking devices. A cleat 25 may also be provided for that purpose on the bottom 11 of the compartment 19, to prevent the shifting and lateral displacement of the lower part of the mounting board 20 within the compartment.

It will be readily apparent that the mounting board or rack 20 may be bodily removed from the compartment 19, with all of the articles in

mounted position thereon, and may be so carried for use at any desired location, without the need of carrying the entire case along, and that such board or rack may be removed from its place either through the top or the front of the compartment 19. It will also be apparent that individual items of cosmetics or toiletries or the like may be readily removed from their place on the board 20, and as readily replaced thereon, while the board is in position within the compartment 19, through the front thereof, by lowering the front wall 14.

For further convenience in the use of the mounting board 20 externally of the case, it may be provided with a pivotally associated supporting back 26, which is secured at its upper edge, and which may be folded up against the board 20 when in position within the traveling case, and which may be angularly disposed relative to the board 20 when out of the traveling case, so that the mounting board 20 may be conveniently set up and supported in substantially upright position, convenient for the removal therefrom and replacement thereon of the articles carried by it, as shown in Fig. 3 of the drawings.

Restraining straps or bands 27 may connect the side edges of the board 20 and supporting back 26, to limit their angular separation and prevent their collapse when set up for use.

In the preferred embodiment of the mounting board shown in Fig. 4 of the drawings, the supporting back 26 is eliminated, the board 20' having a forwardly and laterally extending base 29, which may, preferably, be integrally formed therewith. The board 20' may be supported upon the base in upright position, with the aid of the various receptacles mounted on the board 20' and resting on the base 29, which help keep the board 20' from folding in a forward direction, and with the aid of the bands or straps 30 connecting the side edges of the board and base, which help prevent the folding of the board 20' in a rearward direction.

The board 20' may, likewise, be provided with the straps 22' having the fastening means 24' for securing it to the partition 17, when disposed within the compartment 19.

Such embodiment of Fig. 4 eliminates the need for the cleat 25 on the bottom of the compartment 19, its purpose being served by the hinged wall 14, as will be readily understood, and also makes possible additional, if slight economy in space by eliminating the member 26, the horizontal space being occupied by the base 29, creating no material difference in view of the arrangement and construction of the cover 15, over the compartment 19.

The front wall 14 may be provided with straps 31 on its upper edge, which have fastener elements 32 at their ends. The straps 31 are adapted to be folded over the top edge of the partition 17 to engage cooperating fastener elements (not shown) on the inner face of the partition, and thereby be securely retained in upright position,

to close the front of the auxiliary compartment.

This completes the description of one embodiment of the fitted traveling case of the present invention. It will be readily apparent that such fitted traveling case has the auxiliary compartment conveniently located for use and utilizing a minimum amount of space, because of the upright disposal of the articles carried therein.

It will also be apparent that many modifications and variations may be made in the embodiment illustrated, by any one skilled in the art, in accordance with the principles hereinabove set forth and without the use of any inventive ingenuity. I desire, therefore, to be protected for any and all such modifications and variations that may be made within the spirit of the present invention and the scope of the claims hereto appended.

What I claim is:

- 20 1. A traveling case of the character described comprising a receptacle having a bottom and an upright side wall hinged to said bottom, a partition within said receptacle parallel to said upright hinged wall and dividing said receptacle into compartments, a rack having receptacle receiving portions on one of its faces, said rack being arranged in upright position within the compartment having said hinged wall and against said partition, means for securing said rack to said partition, and means for securing said hinged wall in upright position to said partition.
- 25 2. The traveling case of claim 1, wherein said rack is provided with means for supporting it in upright position externally of the case.
- 30 3. The traveling case of claim 1 wherein the rack is provided with a forwardly extending lateral base and with bands connecting the edges of said rack and said base to keep them at right angles to one another.
- 35 4. The traveling case of claim 1, wherein the rack is provided with a supporting element hinged thereto adjacent its upper edge and adapted to be disposed at an angle thereto to support it in substantially upright position externally of said receptacle, and means for limiting the angle of said rack and its said supporting means relative to one another.

ELIZABETH N. GRAHAM.
